UNITED STATES PATENT OFFICE.

WILLIAM LAYCOCK, OF CHICAGO, ILLINOIS, ASSIGNOR TO THE CHANDLER & TAYLOR COMPANY, OF INDIANAPOLIS, INDIANA.

CROSS-HEAD.

SPECIFICATION forming part of Letters Patent No. 479,818, dated August 2, 1892.

Application filed April 1, 1892. Serial No. 427,409. (No model.)

To all whom it may concern.

Be it known that I, WILLIAM LAYCOCK, a citizen of the United States, and a resident of the city of Chicago, county of Cook, and State 5 of Illinois, have invented certain new and useful Improvements in Cross-Heads, of which the following is a specification, reference being had to the accompanying drawings, in which—

10 Figure 1 is a top or plan view, a part being in section. Fig. 2 is a side elevation of one of the gibs. Fig. 3 is an end elevation of one of the gibs, part being in section. Fig. 4 is a top or plan view of one of the bushes, and 15 Fig. 5 is an end elevation of the same.

My invention relates to cross-heads for engines, and more particularly to the means for securing the cross-heads to the gibs which operate to hold it in position between the 20 usual guides.

The object of my invention is to provide a new and improved cross-head to which the gibs will be adjustably secured and to provide means whereby the gibs may be prevented from working loose and may be readily removed or adjusted. I accomplish these 25 objects as hereinafter specified, and as illustrated in the drawings.

That which I regard as new will be pointed 30 out in the claims.

In the drawings, *a* indicates a cross-head, which is provided on each side with a trunnion *b*.

c indicates bushes, one of which is placed 35 upon each trunnion *b* and fits closely thereupon, as shown in Fig. 1. Each bush *c* is provided with a shoulder *c'* at its inner end, which shoulder is provided with a number of recesses *c''*, as best shown in Fig. 5. By this 40 construction the bush *c* may be turned by using a spanner adapted to engage the notches in the shoulder *c'*. Each of the bushes *c* is split on one side, as shown in Fig. 5, whereby it may be increased or diminished slightly in 45 size in order to loosen or tighten it in position upon its trunnion.

d indicates gibs, which are adapted to receive the trunnions *b* and to slide between suitable guides in the usual manner. The 50 outer or bearing surfaces of the gibs are preferably curved, as shown in Fig. 3; but I do not wish to limit myself to that construction, as they may be made flat or of any other de-

sired shape, the guides in which they move being correspondingly shaped. Each gib *d* 55 is provided with a boss *e*, which is screw-threaded and is adapted to screw upon the bush *c*, as best shown in Fig. 1. Each gib *d* is also provided with a slit *d'*, which extends transversely through it in such manner as to 60 divide the boss *e*, as best shown in Fig. 2. Each boss *e* is perforated on each side of the slit *d'* to adapt it to receive a bolt *f*, which passes through the perforations in the boss *e*, as shown in Figs. 1 and 2. 65

g indicates a nut, which fastens upon the bolt *f*, as shown in Fig. 2. By screwing the nut *g* upon the bolt the slit *d'* may be contracted, thereby tightening the boss *e* upon the bush *c* and also tightening the bush *c* 70 upon the trunnion *b*. By this means the gibs may be tightly secured to the cross-head and cannot readily work loose. When it is desired to adjust the position of the gibs, by unscrewing the nut *g* the gibs may be loosened, 75 and by then screwing the bushes the gibs may be adjusted, as desired.

That which I claim as my invention, and desire to secure by Letters Patent, is—

1. The combination, with a cross-head and 80 trunnions carried thereby, of bushes mounted upon said trunnions and gibs screwed upon said bushes, substantially as described.

2. The combination, with a cross-head and trunnions carried thereby, of split bushes 85 mounted upon said trunnions and gibs screwed upon said bushes, substantially as described.

3. The combination, with a cross-head and trunnions carried thereby, of split bushes 90 mounted upon said trunnions, and gibs, each of said gibs having a boss adapted to screw upon said bushes, and slits in said bosses, substantially as described.

4. The combination, with a cross-head and 95 trunnions carried thereby, of split bushes mounted upon said trunnions, gibs *d*, each of said gibs having a boss *e*, adapted to screw upon said bushes, a slit *d'* in each of said bosses, and a bolt for contracting said slit, 100 substantially as described.

WILLIAM LAYCOCK.
